LEE H. HARLOW, OF LOS ANGELES, CALIFORNIA, ASSIGNOR OF ONE-HALF TO GROVER C. PIPER, OF LOS ANGELES, CALIFORNIA

SINGLE-BUTTON ELECTRIC SWITCH

Application filed October 1, 1927. Serial No. 223,323.

My invention applies to a single button type of switch in which an inward movement of the button caused by pressing on the head makes a connection for one circuit, and the next pressure breaks the circuit; or if desired, two circuits may be connected to the switch so that the inward movement of the button makes one circuit and breaks the other and the next inward movement makes the other circuit and breaks the first circuit, the return movement of the button being automatic, due to a spring action.

An object of my invention is the construction of a single button electric switch by which a switch stem or rod is slidable longitudinally and carries a double acting dog or latch which engages with the pivoted plate on a fixed structure, this being arranged so that in one inward movement of the stem, the dog engages the plate. As the dog is pivotally mounted on the stem it swings the plate downwardly, forming engagement with a pair of contacts, or else breaking a previously made contact. The plate is provided with a slot or opening through which the dog or latch operates and on the tilting movement of the plate, the dog passes through the slot. Then on the upward movement of the stem the dog is brought to a central position by means of a stop plate.

Another feature of my invention is connecting the tilting plate to the frame by a toggle type of spring, this spring having an angular adjustment so that the plate may be retained in its tilted position by shifting the fulcrum point of the spring. The switch may be arranged to operate only in one direction, thus making an immediate make and break, on pressing and releasing of the button.

Another object of my invention is the connection of the indicating pointer operating with the tilting plate to show whether the switch is on or off.

In constructing a switch according to my invention I have a suitable switch box with a metal frame therein. In this frame I have a tilting plate pivotally mounted on trunnions or journals. This plate has an elongated slot in the center transverse the axes

of the journals and through this slot operates the slidable stem of the switch, this stem having a suitable button outside of the case or housing. The stem has a transverse slot in which is located a pivotally mounted dog, this dog being in the form of a thin blade, flat on the lower surface, having a concave arch on the upper surface, with flat surfaces at the ends of the inverted arch to engage a stop plate, and centers the dog on the upward return of the stem.

The side edges of the dog are so shaped that when the stem is forced downwardly and the plate is tilted on one inclination, the lower edge of the dog at one end engages the upper part of the tilted plate. This causes the dog to tilt, assuming the same angle as the plate, and, as the dog has a limited pivotal movement, the plate is forced downwardly and tilted in the other direction. In this action the end of the dog which is tilted downwardly passes through the slot in the plate, and clears this on the upward movement, leaving the plate in its tilted position and with the dog also having the reverse tilt. Then, as above mentioned, on the upward movement of the stem, which is caused by a spring action, the dog is righted by the stop plate, its lower edge assuming a horizontal position.

My invention will be more readily understood from the following description and drawings, in which:

Figure 1 is an end elevation of my switch partly broken away.

Fig. 2 is a horizontal section on the line 2-2 of Fig. 1 in the direction of the arrows.

Fig. 3 is a vertical longitudinal section of the switch on the line 3-3 of Fig. 1 in the direction of the arrows, showing the dog in the position of engaging the tilting plate on the downward movement of the stem.

Fig. 4 is a vertical longitudinal section on the line 4-4 of Fig. 3 in the direction of the arrows, illustrating the stem in its outermost position and with the dog or latch level.

Fig. 5 is a diagrammatic elevation showing the manner of actuating my switch by an electro-magnetic control or the like.

The switch comprises an insulating box or

100

housing 11 which is shown as of rectangular construction and having a cover plate 12 attached thereto in any suitable manner. A metal frame 13 constructed inside the box has a base plate 14, a pair of vertical side plates 15 and a horizontal stop plate 16 at the top. The base plate has a squared or other angular opening 17 therethrough and the stop plate, also has an opening 18 which may be circular or any other suitable shape. A pair of longitudinal metal plates 19 are connected across the vertical plates 15 at the bottom, and on these there is an insulating plate 20 and then a conducting strip 21, which has outwardly bent arms 22 with U-shaped fins 23 forming a socket for a knife blade type of switch, as hereunder mentioned. An insulating cover plate 24 is on the outside of the above mentioned assembly, the whole being secured in position by bolts 25 or the like.

There are four assemblies as above described, giving four sockets for knife-blade switches; two of these, however, if desired, may be dummies, or they may be all electrically connected. In order to afford this construction I have the conducting plates 21 of the bottom set each provided with a conducting extension 26 which has the free ends 27 extending outside of the housing and allowing connection with electric wires. Each of the upper conducting plates 21 is also provided with an extension 28. These, however, terminate inside the box and have conducting bars 29 secured thereto by bolts 30, or the like, these latter having their free ends 31 extending outside of the insulating housing and allowing connection to electric lead wires. The arrangement of the fixed sockets being illustrated in particular in Fig. 3 and the outside connections being shown in Figs. 1 and 2.

A switch stem 35 is slidably mounted in the metal frame and has its upper section 36 having a sliding fit in the opening 18 in the stop plate 16, and its lower end 37 preferably formed square or of irregular section and sliding in the opening 17 in the base plate 14, this preventing rotation of the stem. The button 38 is secured to the stem and has an insulating skirt 39 sliding through an opening 40 in the cover plate 12, thus being insulated therefrom. This stem is provided with a transverse slot 41 in which is mounted a dog 42. This dog is a thin plate and has a flat lower edge 43. The upper edge has a central concave section 44 forming an inverted arch with flat tips 45 at the ends. The side edges have a concave curve 46 with a straight part 47 adjacent thereto, leading to the bottom edge. The dog is mounted on a pintle 48 and there is sufficient friction to retain the dog in any of its various positions, as hereunder set forth. It will be noted that in the tilted position of Fig. 3 the concave edge 44 of the dog engages with the corner 49 of the upper edge 50 of the slot 41, and also when the stem

is in its outer position, the flat surface 45 on the upper edge of the dog engages the plate 16, centering the dog in the position shown in Fig. 4. The action of the stem in being forced outwardly is due to the spring 51 which engages the base plate 14 and a ring 52 which is thrust upwardly against the shoulder 53 on the stem.

The tilting plate 55 may be of any suitable shape but is illustrated as being rectangular and having trunnions 51' on opposite sides, which are mounted in journals 52' on the vertical plates 15 of the frame 13. This plate has a central opening or elongated slot 53' through which the stem 35 passes. The tilting plate has an insulating strip 54 thereon and a conducting strip of metal 55' on the insulating strip, this metal terminating in knife-like blades 56 on opposite sides, these blades having upper and lower wings, as illustrated in Figs. 3 and 4, such wings engaging in the sockets 23 to make the electrical connection.

Rigidly connected to the trunnion 51' on one side there is a depending arm 57 which has a bent end 58 at its lower end, this bent end engaging in a socket 59 on a short rod 60, which is slidable through an opening in the bracket 63. This rod has a shoulder 61 against which thrusts the compression spring 62, this latter spring being connected to the bracket 63 supported by a bolt 63' which extends through a slot 64 through one of the plates 15.

This construction allows shifting of the supporting bolt, having it either in the plane of the center of the swindle or shifted to one side or the other of the slot. A pointer 65 is rigidly connected to the tilting plate and extends upwardly through a slot 66 in the cover plate 12 so that this is visible in the top and may be felt with the finger in the dark to indicate the position of the switch.

The manner of operation and functioning of the switch is substantially as follows:

Presuming that the switch is in the position shown in Fig. 4, when the button is thrust inwardly, this moves the stem 35 inwardly and brings one end of the dog into engagement with the solid part of the plate, as shown in Fig. 3, this plate being tilted. As the upper concave edge 44 of the dog is in engagement with the corner 49 of the stem, the dog has a resistance and on a further downward movement pivots the tilting plate, disconnecting the wings of the knife-like blades from the sockets 23 which are of resilient or spring-like nature. The action forces the tilting plate downwardly until the opposite pair of sockets are engaged by the opposite blades on the tilting arm and in this action the dog oscillates on its pivot, the opposite side of the dog passing through the slot 53.

When the button is released, the spring 130

forces the stem outwardly carrying the dog upwardly, which remains in a tilted position due to its frictional fitting in the slot 41 of the stem and on the pivot 48, so that the side 5 which is below the tilting plate lifts through the slot 53 without contact with the tilting plate; hence without shifting the dog. In its uppermost position the dog is again leveled or centered, as shown in Fig. 4.

10 The spring 62 acting on the arm 57 acts as a toggle device and when the bolt 63' is centered in the slot 64, the pressure of the spring tends to keep the tilting plate in the position to which it has been shifted. Therefore, the 15 switch remains in this position until the next inward movement of the stem, which action reverses the position of the dog to accommodate it to the position of the tilted plate, and on the further inward movement of the stem 20 tilts the tilting plate back to the position shown in Figs. 3 and 4.

It will be obvious that if I wish my device 25 to function as a single pole, single throw switch, I may have two electric leads, one connecting electrically to one of the lower sockets 23 and the other to the upper socket 23 on the opposite side, leaving the other two sockets as dummies, without any electrical connection. If, however, I wish to have the 30 switch function as a single pole, double throw switch, each of the sockets 23 will be connected to electric leads, these being attached to diametrically opposite sockets. Also, if desired, I may make the switch into a three-way 35 switch by forming a connection between one of the upper sockets and one of the lower sockets on the same side of the switch.

If it is desired to have the switch operate 40 as a releasing switch, that is, to release or open the circuit immediately after releasing the button, the bolt 63' is shifted in the slot 64 towards one end or the other of such slot, in accordance with the electrical connection. Then when the stem is pressed downwardly, 45 the tilting plate is shifted into position on the incline, forming a connection which has the conducting element 55 and on release of the button, the spring 62 forces the tilting plate back into its original position.

50 In Fig. 5 I show an electrically controlled arrangement for operating the switch. In this case the switch is designated generally by the numeral 70 and electro-magnetic device by the numeral 71. A post 72 supports a lever 73 which has an armature 74 thereon, this lever being normally tilted upwardly by the tension spring 75 attached to the end of the arm, and to the base 76. The arm has an adjustable set-screw 77 at its free end 55 which engages with the button 38 and thrusts the stem inwardly when the electro-magnetic device 71 is energized. This construction gives a remote control of the switch which may be utilized for many purposes, as momentarily energizing the electro-magnetic

device 71, which thrusts the stem inwardly, thus actuating the switch. It is manifest that this switch may be wired in any of the ways above described, or in any other suitable manner to give the electrical circuits contemplated. 70

Various changes may be made in the principles of my invention without departing from the spirit thereof, as set forth in the description, drawings and claims. 75

I claim:

1. An electric switch comprising a structure having fixed contacts, a pivotally mounted substantially flat plate thereon having movable contacts to engage with the fixed contacts, said plate having a slot therein, a slidably mounted stem extending through the slot and having a dog pivotally mounted directly thereon, said dog engaging the plate when tilted in one position and on the movement of the stem in one position tilting the plate into another position, thereby making or breaking a connection between the fixed and movable contacts, said dog passing partly through the said slot in the plate. 80 85 90

2. In the art described, the combination of a structure having fixed contacts, a pivotally mounted substantially flat plate having movable contacts thereon to engage with the fixed contacts, said plate having a slot therein, a slidably mounted stem extending through the said slot, said stem having a transverse slot therein with a dog pivoted directly in the latter slot, said dog having a lower edge to engage the tilted plate and tilt the dog on inward movement of the stem and tilt said plate from one inclination to the opposite inclination, the slot in the plate and the dog being constructed to form a clearance on the return movement of the stem, said dog passing partly through the said slot in the plate. 100 105

3. In the art described, as claimed in claim 2, and a stop plate mounted in the fixed structure to shift the dog from a tilted position to a transverse position in relation to the stem 110 on the outward movement of the stem.

4. In the art described, the combination of a fixed structure having fixed contacts, a pivotally mounted substantially flat plate having moving contacts to engage with the fixed contacts, a stem, a dog pivotally mounted directly thereon, said dog engaging the plate when inclined and tilting the plate to the opposite inclination on the inward movement of the stem, said movement also tilting the dog, and means on the return movement of the stem to move the dog from the tilted to a transverse position relative to the stem. 115 120

5. A switch having a fixed structure with fixed contacts, a pivotally mounted plate with moving contacts, said plate having a slot therein, a stem slidably movable through the slot and having a dog pivotally mounted directly thereon, such dog engaging the tilting plate on the inward movement of the stem 125 130

and tilting said plate from one inclination to the opposite inclination, said movement also tilting the dog, and a stop plate to engage the dog on the outward movement of the stem and shift the dog from an inclined position to a uniform transverse position relative to the stem.

6. A switch comprising in combination a fixed structure having fixed contacts, a pivotally mounted substantially flat plate having moving contacts, a stem slidable in relation to the pivoted plate, said stem having a dog pivotally connected directly thereto, the contacts being engaged when the plate is tilted, the lower edge of the dog engaging the upper part of the tilted plate and tilting the dog on the inward movement of the stem and tilting said plate to an opposite inclination, the dog having an upper edge contacting with part of the stem in such movement, and means to return the stem to its original position.

7. A switch as claimed in claim 6, the dog passing partly through a slot in the plate and the side edges of the dog being shaped to pass free of the plate on the upward movement of the stem, and means to shift the plate from a tilted to a straight transverse position.

8. A switch comprising in combination a fixed structure having a plurality of fixed contacts, a pivotally mounted plate having an opening therein and moving contacts, a stem slidably mounted through the opening in the plate having a transverse slot, a dog pivotally mounted in said slot, said dog having a flat base, a concave curve on the upper edge, concave curves on the side edges, said dog contacting with the upper part of the plate when tilted on the inward movement of the stem and tilting said plate to a reverse position, the said dog also tilting into a reverse position, the side edges of the dog clearing the plate at the opening in such movement, means to return the stem to its original position, and means to shift the dog from a tilted to a directly transverse position relative to the stem.

9. A switch having a fixed structure with a plurality of fixed contacts, a pivotally mounted plate having moving contacts, a spring and an arm forming a toggle connection between a fixed structure and a plate, and means to shift the spring relative to said fixed structure, a slidably mounted stem having a dog pivotally mounted directly thereon to engage the plate and tilt the plate from one direction to the other on the movement of the stem in one direction.

10. A switch comprising in combination a frame having a pair of side plates, a plurality of fixed contacts secured to the frame, a plate pivotally mounted in the side plates and having an opening therethrough, moving contacts attached to said plate, a stem slidably mounted in the frame and extending through

the opening in the plate, a dog pivotally mounted on the stem to engage the plate and tilt same from one inclination to the opposite inclination, one of the said plates having a slot, a bracket having means connecting same through the said slot, an arm connected to the tilting plate, and a spring connected between the bracket and the said arm.

In testimony whereof I have signed my name to this specification.

LEE H. HARLOW.
